DESIGN FOR A SHOWER HEAD ATTACHMENT FOR BATH SALTS

Otto d'Algoda, Basking Ridge, N. J.

Application January 12, 1945, Serial No. 117,386

Term of patent 14 years

(Cl. D91—1)

To all whom it may concern:

Be it known that I, Otto d'Algoda, a citizen of the United States, residing at Basking Ridge, in the county of Somerset and State of New Jersey, have invented a new, original, and ornamental Design for a Shower Head Attachment for Bath Salts, of which the following is a specification, reference being had to the accompanying drawing, forming part thereof.

Fig. 1 is a perspective view of a shower head attachment for bath salts showing my new design, in one position thereof;

Fig. 2 is a top plan view of the attachment shown in Fig. 1;

Fig. 3 is a perspective view of the attachment shown in Fig. 1 in another position thereof;

Fig. 4 is a bottom perspective view of the device shown in Fig. 1.

I claim:

The ornamental design for a shower head attachment for bath salts, as shown.

OTTO D'ALGODT.
